DESIGN FOR A CHILD'S CART

Garard Renzelman, Denver, Colo.

Application May 27, 1946, Serial No. 130,123

Term of patent 7 years

(Cl. D14—3)

To all whom it may concern:

Be it known that I, Garard Renzelman, a citizen of the United States, residing in the city and county of Denver and State of Colorado, have invented a new, original, and ornamental Design for a Child's Cart, of which the following is a specification, reference being had to the accompanying drawing, forming part thereof.

In the drawing:

I claim:

The ornamental design for a child's cart, as shown.

GARARD RENZELMAN.
